UNITED STATES PATENT OFFICE.

BENJAMIN BAYLISS, JR., OF BELTZHOOVER, PENNSYLVANIA.

MANUFACTURING IRON AND STEEL.

SPECIFICATION forming part of Letters Patent No. 313,079, dated March 3, 1885.

Application filed October 8, 1884. (No model.)

To all whom it may concern:

Be it known that I, BENJAMIN BAYLISS, Jr., of Beltzhoover, in the county of Allegheny and State of Pennsylvania, have invented 5 new and useful Improvements in the Art of Manufacturing Iron and Steel, of which the following is a full, clear, and exact description.

My invention relates to the purification of 10 iron and the manufacture of steel; and its objects are, first, to decrease the number and time of existing reducing operations; second, to secure within a comparatively short period approximately perfect desiliconization; third, 15 to obtain an intimate commixture of the mass with any alloys that may be added; fourth, to simplify and economize the construction of converters; fifth, to secure automatically a uniform current of carbonic acid or air without reference to the upright or reverse position of the converter; and, sixth, to attain these ends with simplicity of plant. I accomplish these objects by the means illustrated in the accompanying drawings, in which--

25 Figure 1 is a front elevation of the converter and appurtenances. Fig. 2 is a vertical section thereof. Fig. 3 is a rear elevation. Fig. 4 is a transverse section on the line $x-x$ of Fig. 3. Fig. 5 is a detail transverse section of the air-supply chamber. Fig. 6 is a detail view of the runner by which the liquid mass is conducted from the converter, showing the means of its attachment to the mouth of the converter. Fig. 7 is a vertical section 30 of the same, and Fig. 8 a transverse section thereof. Fig. 9 is a detail view of the stopper inserted in the mouth of the converter to conserve the heat between successive discharges and charges.

40 The same designations signify the same parts in all the views.

A B C are sections constituting, when united, the converter. A concentric chamber, b'' , surrounds the section A, to serve for the introduction of air to the tuyeres b' , which open into the recess b on one side and into the converter on the other. Hand-holes $c c$ afford access to the interior of this chamber, as well for cleansing purposes as for the renewal of 45 defective tuyeres. The sections A C terminate at both ends in flanges $a a$, and plates $a'' a''$ are joined to the outer flanges by luting

and bolts $a''' a'''$, to serve as bases. The section B also has flanges on each end, but these project beyond the shell as well inwardly at 55 $a' a'$, to serve as a support for the fire-brick, as outwardly at $a a$, to attain facile joinder to the contiguous sections. When the sections are superposed, the respective flanges of A B and B C are bolted together and luted with 60 refractory material. Lugs $c'' c''$ serve as means for handling the sections by passing chains, operated by suitable mechanical apparatus, under them. In building up the sections, a suitable base, a'' , is joined to A and C. They 65 are then inverted, and fire-brick is placed therein in the manner illustrated in Fig. 2. In section A space to insert the tuyeres must be left. Bricks of different lengths should be used in constructing section B, so that a central contracted area may be provided in the 70 form of two conical frusta united at their smaller bases.

D are suitable standards constituting bearings for the trunnions $d d$, which project from 75 the section B. A chamber, F, surrounds one of the trunnions, but is rigidly secured to the standard D, in order to afford a continuous supply of air from the source, through pipe G to the chamber b'' by means of sections $e e'$. 80 Projections $d'' f'$, respectively, from the section B and from the chamber F inwardly, fit into corresponding grooves, $d' f''$, respectively, of the chamber F and of the trunnion, thus permitting the free rotation of the latter. Flanges 85 $c' c'$ serve as means of joinder of the sections $b'' e e'$, and thus constitute a continuous path for the passage of air. To the mouth g' a suitable runner, I, having an outlet, i' , perpendicular thereto, may be attached by passing 90 the ends of flexible or other connections h'' over the lugs $h h' h''$, respectively, on the mouth-wall g' and the runner I. The chamber F is attached to section B by bolting its flanges $a a$ thereto. It is composed of counterpart halves. Thus arranged, I charge fuel 95 to the converter until the same is highly heated, aiding this by a blast of air. I then invert the vessel by imparting motion, by a belt or other means, to the trunnion d , discharge the 100 fuel, reverse the inclination of the vessel, attach the runner I respectively to a reverberatory or other furnace and to the mouth g' , then charge the molten iron, admit air-blast

to intensify the temperature of the vessel, reverse the vessel several times to accomplish desiliconization and intermixture or homogeneity of the metal, with or without any alloy that may be added, and finally discharge the mass by the runner I to pig-beds or casting-molds, according to the form desired.

I am aware that heretofore the process substantially of heating the converter, then charging the mass, subsequently agitating the same, and finally discharging the purified metal has been employed; but neither the sequence of steps nor the means by which they are effected described and shown by me have been employed.

Heretofore it has been customary in agitating the mass to employ two connected chambers for the alternate reception of the liquid mass actuated and influenced by distinct and different gaseous currents; or the mass was subjected to different currents alternately by periodically reversing a cylinder containing the same, having a smaller central than end diameter, thus virtually making two connected chambers. The same end is attained by me with greater simplicity of apparatus, in that I employ one cylinder of nearly the same diameter throughout, whereby homogeneity is accelerated, and with greater facility and economy of process, because of using but one air-current, as more specifically delineated in the claims.

Having thus fully described my improvements, what I claim, and desire to secure by Letters Patent of the United States, is—

1. In the manufacture of crude iron into iron of higher grade or steel, the process herein described, which consists in introducing fuel to the converter through a suitable inlet when the annular tuyere-chamber is at the bottom, then inverting the vessel, subsequently admitting an air-blast, maintaining this condition until the pressure of the flame inside exceeds that of the atmospheric air surrounding the said inlet, cutting off the air-blast, then inverting the vessel to allow the automatic exit of the fuel through the same aperture to yield the entire space for the metal, reversing the angle of the vessel, charging the liquid metal with or without the addition of heated scrap-iron, again admitting the air-blast, again inverting the vessel so that the metal comes in contact with the tuyeres, maintaining this condition until the color of the flame evidences the completion of the blowing operation, charging any desired alloy, again

admitting the air-blast, inverting the vessel several times to secure perfect commixture, finally inclining the vessel, and discharging the mass therefrom so that in its course to the pig-bed or casting-molds it shall traverse perpendicular paths, for the purpose specified.

2. The sections A C, provided both with flanges at the respective ends, in combination with the section B, having flanges on both ends projecting in either direction from the shell, for the purpose set forth.

3. The section B, lined so as to form a central contracted area, as shown, having flanges *a a' a'* for the purpose set forth, and provided with rim *d''* and recess *e*, in combination with the section A, having air-chamber *b''*.

4. The section C, having mouth *g'*, surrounded by wall *g''*, from which lugs *h h* project, and flanges *a a*, in combination with the runner I and sections A B.

5. The chamber F, composed of counterpart halves having projection *f'*, fitting in groove *f''*, formed by two annular collars around the trunnions, in combination with the section B, having annular rim *d''*, sliding in groove *d'* in the chamber F, and pipe G.

6. The runner I, having lugs *h' h'* and perpendicular outlet *i*, in combination with connections *h'' h''* and lugs *h h*.

7. The section A, having flanges at both ends and provided with an annular tuyere-chamber, *b''*, in combination with the section B, having flanges at both ends projecting in either direction beyond the shell, having a contracted central area, and trunnions *d d* radiating from its surface, section C, having flanges at either end, and a mouth, *g'*, and standards D D, forming bearings for the trunnions.

8. The standards D D, constituting bearings for the converter, in combination with the section B, having flanges *a a' a'* on both ends, projecting beyond the shell in either direction, provided with trunnions *d d*, on one of which are two annular collars, forming a groove, *f''*, between them, and the end of the other serving for the reception of rotary motion from suitable mechanical media, chamber F, pipe G, passages *e e'*, and chamber *b''*, the whole co-operating in the manner shown, and for the purpose specified.

BENJAMIN BAYLISS, JR.
